UNITED STATES PATENT OFFICE

96,830

DESIGN FOR A LACE COVERING

Morris Greenberg, Brooklyn, N. Y.

Application June 17, 1935, Serial No. 57,290

Term of patent 3½ years

To all whom it may concern:

Be it known that I, Morris Greenberg, a citizen of the United States, residing in Brooklyn, county of Kings, and State of New York, have invented a new, original, and ornamental Design for Lace Coverings, of which the following is a specification, reference being had to the accompanying drawing, forming a part thereof, in which

Fig. 1 is a diagrammatic view of the complete covering, shown on a smaller scale and

Fig. 2 shows substantially one half of the lace covering disclosed in Fig. 1 but illustrating the details of the design on a larger scale, the part of the lace covering not shown being repeated in proper relation to complete the covering.

According to the design illustrated in Figs. 1 and 2, the dominating characteristic feature resides in the provision of a covering having a rim of lace comprising an outside stepped border, and an intermediately and centrally disposed linen portion having a stepped border connected to the inner edge of the rim.

I claim:—

The ornamental design for a lace covering, substantially as shown and described.

Signed at New York, in the county of New York and State of New York this 15th day of June 1935 A. D.

MORRIS GREENBERG.
